UNITED STATES PATENT OFFICE.

FRANK X. WEHRLE, OF THOMASTON, CONNECTICUT, ASSIGNOR TO THE SETH THOMAS CLOCK CO., OF THOMASTON, CONNECTICUT, A CORPORATION.

SHIP'S-BELLS CLOCK.

1,394,957.

Specification of Letters Patent. Patented Oct. 25, 1921.

Application filed May 4, 1921. Serial No. 466,777.

To all whom it may concern:

Be it known that I, FRANK X. WEHRLE, a citizen of the United States, residing at Thomaston, in the county of Litchfield and 5 State of Connecticut, have invented a new and useful Improvement in Ships'-Bells Clocks; and I do hereby declare the following, when taken in connection with the accompanying drawings and the characters of reference marked thereon, to be a full, clear, and exact description of the same, and which said drawings constitute part of this application, and represent, in—

Figure 1 a view in rear elevation of a 15 ship's bells clock-movement embodying my invention with its parts shown immediately after their release for striking "six bells."

Fig. 2 a view thereof, with the parts shown in the positions due to them after 20 "six bells" have been struck.

Fig. 3 a plan view thereof.

Fig. 4 a view corresponding to Fig. 1, but showing the parts in the positions due to them after striking "seven bells."

25 Fig. 5 a detached perspective view of the rack-lever.

Fig. 6 a corresponding view of the ship's bells-lever.

Fig. 7 a corresponding view of the ship's 30 bells-cam.

My invention relates to an improvement in ship's bells clocks of the rack-and-snail type, in which the bells are struck in pairs, the object being to produce a reliable clock 35 of the character described, constructed with particular reference to reducing the number of parts, pertaining to the ship's bells mechanism, to the minimum.

With these ends in view, my invention 40 consists in a rack-and-snail ship's bells clock in which the bells are struck in pairs and characterized by having a ship's bells-lever pivotally mounted upon the rack-lever and coacting with a ship's bells-cam timed and 45 arranged to nullify one stroke of the hammer at the half hours.

My invention further consists in the construction and arrangement of parts as will be hereinafter described and pointed out in 50 the claims.

In carrying out my invention, as herein shown, I employ a ship's bells-lever 10, pivotally mounted by a pivot 11 upon a rack-lever 12 provided at its outer end with a hub 55 13 by which it is loosely mounted upon the

projecting rear end of the shaft 14 of the warn-lever 15, the bent inner end 16 of which coacts in the usual manner with a stop-pin 17 in the fifth wheel 18 of the strike-train, which may be of any suitable 60 construction and arrangement. The said ship's bells-lever 10 is formed with a vertical slot 19 receiving a headed rivet 20 carried by the rack lever 12 and limiting the rocking movement of the lever 10 upon its 65 pivot 11. The said lever 10 extends beyond the inner end of the rack-lever 12 to the opposite edge of the rear movement-plate 21, and is bent to form a cut-out finger 22, which coacts with an upstanding cut-out hook 23 70 provided with a hub 24 by means of which it is mounted upon the projecting rear end of the hammer-shaft 25, which carries the hammer-arm 26, which is furnished with an adjustable hammer 27. A stop-pin 28, in 75 the rear movement-plate 21, is positioned to engage with the lower edge of the outer end of the ship's bells-lever 10 to limit the downward movement of both levers. A ship's bells-cam 29, directly coacting with the under edge of the ship's bells-lever 10 at the point 30 thereon (Fig. 6), is arranged to successively present one of its flat clearance-faces 31 to the said lever on the half hours and one of its high-points 32 on the hours. 80 As shown, this cam is a three-point cam and timed to make a complete revolution once in three hours, being located at the inner end of the sleeve 33 of the ship's bells dial-wheel 34, which is revolved once in three 85 hours by a minute pinion 35 upon the projecting rear end of the center-shaft 36. The said wheel 34 carries a pinion 37 meshing into and driving an hour-wheel 38 turning upon the rear end of the center-shaft and 90 carrying a snail 39, the periphery of which is divided into three corresponding series of steps plotted on the plan of ship's bells and coacting with the pointed finger 40 of the rack-controlling arm 41 of the rack-arm 42, 100 which rocks upon a stud 43 and is provided at its upper end with a rack 44, the teeth of which are entered by the count-hook 45 of the rack-lever 12. The teeth of the rack are successively engaged for lifting the rack 105 by means of the usual gathering-pin 46 in a gathering-hub 47, mounted upon the projecting rear end of the shaft 48 of the fourth wheel 49 of the strike-train. The rack-lever 12 is also provided with the usual stop-fin- 110

ger 50, which is bent at a right angle and extends forwardly through a slot 51 in the rear movement-plate 21 into position to engage with the stop-pin 17 upon the fifth wheel 18 aforesaid. The rack-lever 12 is lifted every half hour to release the rack and thus permit the clock to strike, by means of a lifting-finger 52 projecting rearward through an opening 53 in the plate 21 and forming a part of the warn-lever 15, which is lifted every half hour through the medium of a warn-actuating lever 54 mounted upon the rock-shaft 14 and bent at its lower end to coact with a two-point cam 55, making a complete revolution every hour and mounted upon the center arbor 36. The operation of warning and releasing the strike-train takes place in the ordinary manner of such clocks.

For convenience in describing the operation of my improved clock, reference may first be had to Fig. 1, which shows its parts in the positions which they will have just after the strike-train is released, preparatory to striking "six bells." It will be noticed that the ship's bells-lever 10 has been lifted with the rack-lever 12 and that one of the high points 32 of the ship's bells-cam 29 is presented to its under face. At the conclusion of striking "six bells," the parts will be in the positions shown in Fig. 2, in which it will be noticed that the point 30 of the ship's bells-lever 10 rests upon the upstanding high point 32 of the cam 29. The same cycle of movement is again repeated and "seven bells" are struck, at the conclusion of which the parts will have the positions shown in Fig. 4, in which it will be noticed that on account of the presentation of one of the clearance-faces 31 to the point 30 of the lever 10, the same has been allowed to fall into a sufficiently depressed position to have its cut-out finger 22 engaged by the cut-out hook 23 upon the hammer-shaft, whereby the same although it goes through the rocking movement for striking "eight bells," is prevented from falling far enough to permit its hammer 27 to strike upon the last count, so that "seven bells" are rung rather than "eight." By

the mechanism described, it appears that one stroke of the hammer is virtually nullified at the half hours. In other words, the mechanism, although constructed to strike the bells in groups of two bells, nullifies one stroke of a pair of strokes on the half hours. 55

I claim:

1. A rack-and-snail ship's bells clock in which the bells are struck in pairs, having a rack-lever, a substantially horizontal ship's bells-lever pivotally mounted between its ends thereupon in line therewith, a hammer controlled by the ship's bells-lever, and a ship's bells-cam timed and arranged to nullify one stroke of the hammer at the half hours. 60

2. A rack-and-snail ship's bells clock in which the bells are struck in pairs, having a rack-lever, a substantially horizontal ship's bells-lever pivotally mounted between its ends thereupon in line therewith, a hammer, a cut-out lever connected with the hammer and directly coacting with one end of the said ship's bells-lever, and a ship's bells-cam timed and arranged to permit the ship's bells-lever to coact with the said cut-out lever every half hour and to prevent such coaction on the hours. 75

3. A rack-and-snail ship's bells clock in which the bells are struck in pairs, a rack-lever, a substantially horizontal ship's bells-lever pivotally mounted between its ends thereupon in line therewith, a hammer, a cut-out lever connected therewith and directly coacting with one end of the said ship's bells-lever, and a cam having high points and clearance-faces and coacting with the ship's bells-lever to permit the same to coact with the cut-out lever on the half hours and to prevent its coaction therewith on the hours, the said cam revolving once in three hours. 80 85 90

In testimony whereof, I have signed this specification in the presence of two subscribing witnesses.

FRANK X. WEHRLE.
